UNITED STATES PATENT OFFICE.

FRANK L. CHASE AND BERTRAND M. YOUNG, OF JAMESTOWN, NEW YORK; SAID YOUNG
ASSIGNOR TO SAID CHASE.

MULTIPLE-CYLINDER ENGINE.

No. 877,294.

Specification of Letters Patent.

Patented Jan. 21, 1908.

Application filed May 28, 1904. Serial No. 210,160.

To all whom it may concern:

Be it known that we, FRANK L. CHASE and BERTRAND M. YOUNG, citizens of the United States, residing at Jamestown, county of Chautauqua, State of New York, have invented a certain new and useful Improvement in Multiple-Cylinder Engines, and declare the following to be a full, clear, and exact description of the same, such as will enable others skilled in the art to which it pertains to make and use the same, reference being had to the accompanying drawings, which form a part of this specification.

Our invention relates in general to multiple cylinder engines, and more particularly to that class of such engines in which the cylinders are arranged in aligned pairs on opposite sides of the crank shaft.

It is desirable in multiple cylinder engines, especially of the four-cycle type, that the cylinders should be so arranged with respect to the crank shaft and the cycles of operation of the several cylinders so relatively timed as to effect a complete balancing of the engine, thereby reducing to a minimum the strain incident to the expansion of the motive fluid in the cylinders.

In engines as usually constructed it is necessary either to provide cross heads to guide the pistons and maintain the same concentrically within the cylinders, and to provide a separated connecting rod for operatively uniting each cross head to the crank shaft, or to construct elongated or trunk pistons which will, by means of their length, guide themselves and maintain a position nearly, but not exactly, concentric with the cylinders.

An object of our invention is to provide a multiple cylinder engine of the four-cycle type in which the expansion of the motive fluid occurs simultaneously in cylinders located on opposite sides of the crank shaft and at each half revolution of the crank shaft.

A further object of our invention is to provide a multiple cylinder explosive engine in which the valve mechanism is simple and occupies such a limited space as to adapt the engine for use on vehicles in which only a compact motor may be employed.

A still further object of our invention is to provide a multiple cylinder engine which will be simple in construction, comparatively

inexpensive in manufacture, and efficient in 55 operation, and one which can be operated at will in either direction.

A further object of our invention is to provide a multiple cylinder opposed engine wherein the friction between the pistons and 60 cylinder walls is greatly reduced and not affected by the weight of the pistons and reciprocating parts and is not greatly affected by imperfect lubrication of the cylinders, and the wear due to the friction is transferred and 65 confined to a particular location removed from the heated portions of the engine, where lubrication can be properly provided for and where adjustment and compensation for 70 wearing can easily be made.

Our invention will be more fully described hereinafter with reference to the accompanying drawings in which the same is illustrated as embodied in a convenient and practical 75 form, and in which—

Figure 1 is a horizontal sectional view; Fig. 2 a longitudinal vertical section on line 2—2, Fig. 1; Fig. 2^a a detail sectional view of the guide bearing for the yoke; Fig. 3 an end elevation looking from the left in Figs. 1 and 2, part of the crank casing being broken away; Fig. 4 a plan view of the valve actuating rods; Fig. 5 an elevational view of the spiral gears for actuating the valve mechanism from the crank shaft; Fig. 6 an end elevational view of one of the cam shafts; Fig. 7 a detail view of a modified form of yoke; Fig. 8 a sectional view on line 8—8, Fig. 7; and Fig. 9 a detail sectional view on line 5^a—5^a, 90 Fig. 5.

The same reference characters are used to designate the same parts in the several figures of the drawings.

Reference characters A' to A⁸ indicate the cylinders of the engine which are arranged 95 in opposite aligned pairs between which is located a crank shaft C.

c designates a fly wheel fixed to the crank shaft.

C', C³, C⁵, and C⁷ designate cranks on the 100 shaft C each of which is interposed between the aligned cylinders of an opposed pair. The inner ends of the cylinders are connected to the side walls d of the crank casing.

D indicates the top of the casing and D' the 105 bottom.

d' designates a bearing in one of the end walls D' of the crank casing in which the shaft

C is journaled, while d^5 indicates a bearing surrounding the crank shaft and carried by the opposite end wall D⁵ of the casing.

D², D³ and D⁴ designate webs within the 5 crank casing and in which are formed bearings d², d³, and d⁴ respectively for supporting the portions of the crank shafts between the cranks thereon.

B' to B⁸ designate the pistons within the 10 respective cylinders A' to A⁸. The pistons in the alined cylinders in each pair are rigidly connected to a yoke B formed in two vertical portions united by tie bolts b. Each part of the yoke is preferably formed integrally with 15 a piston rod rigidly connected to the corresponding piston. Each of the cranks of the shaft is provided with a crank box c³ surrounding the same and guided within the corresponding yoke. In order to relieve the 20 cylinder walls from the weight of the pistons and connecting reciprocating parts, and to concentrate the wearing surfaces at a place removed from the heated portions of the engine where all adjustment and lubrication 25 can be provided for, wedge blocks D⁸ bearing on inclined surface of D⁶ are provided which may be adjusted and locked relatively to the yoke B by means of set screws d⁷ and d⁸, thereby maintaining the requisite support 30 of the reciprocating parts and enabling the wear between the lower end of the yoke and the casing to be compensated for.

Each of the heads of the cylinders is provided with two openings a' and a³ in one of 35 which a spark plug may be inserted, while the other is adapted to receive a relief valve. The spark plug and relief valve are not shown as they form no part of our present invention.

40 a² designates an opening leading to the cooling space around the cylinder and is adapted to be closed by a plug.

Located in each of the cylinder heads is an intake valve F from which depends a valve 45 stem f guided in a sleeve g formed integrally with a detachable cap G, the latter serving as a seat for the intake valve. f' designates a spring which surrounds the valve stem and seats the intake valve. The cap G is provided with a tie bolt g' extending through the 50 same into a screw threaded recess in the cylinder head, as clearly shown in Fig. 2.

E designates the exhaust valve located in each cylinder head which is provided with an 55 upwardly projecting stem e guided in a sleeve formed integrally with the cylinder head.

e' designates a spring surrounding the stem e the tension of which seats the exhaust valve.

a designates an exhaust passage leading 60 through the cylinder head to the valve chamber.

Above each cylinder head is mounted a pair of brackets H' between which is journaled a bell crank lever H. h² designates a 65 rod upon which the bell crank lever H is piv-

otally mounted. One end h of the bell crank lever projects above the upper end of the valve stem e of the exhaust valve of the corresponding cylinder. The opposite arm of the bell crank lever is provided with an anti-frictional roller h' adapted to be engaged by a cam to oscillate the bell crank lever and unseat the exhaust valve.

K' and K² designate rods extending through and journaled in the pairs of brackets H'. The rods K' and K² have fixed thereon cams adapted to engage the bell crank levers. The cams k', k³, k⁵ and k⁷ fixed upon the rod K' are arranged 90° apart, as clearly shown in Fig. 6, while the cams k², k⁴, k⁶ and k⁸ fixed upon the rod K² are also arranged 90° apart, so that the exhaust valves of the cylinders at each side of the crank shaft will be successively opened.

L designates a longitudinal shaft the opposite ends of which are provided with beveled gears l' and l² which mesh with corresponding beveled gears fixed to the ends of the cam rods K' and K². The rod L may be supported in any suitable manner, such for instance 85 as bearings L' projecting inwardly from the end wall D' of the crank casing.

l² designates a small spiral gear which meshes with a large spiral gear C² fixed upon the crank shaft C. The pitch of the spiral 95 threads on the meshed gears l² and C² is such that two rotations of the crank shaft effects a single rotation of the rod L.

Attached to the rod L is a key l which is placed within a wide key-way in the spiral gear l². The width of this key-way being 100 90° plus the width of the key itself minus the amplitude of the necessary lead. The spiral gear l² is thus permitted a movement around the rod L of nearly 90°.

In Figs. 7 and 8 we have illustrated a means for taking up the wear incident to the movement of the crank box c³ within the yoke to which the alined pistons are connected. In such figures N designates the 110 yoke made in two parts and united by tie bolts n.

n' designates a vertical channel formed in the portion of one of the parts of the yoke in which extends a tongue of a wedge block N'. The portions of the wedge block at each side of the tongue are inclined and engage inclined flanges at either side of the groove n' in the yoke. The wedge block N' may be vertically 115 adjusted to take up the wear by means of a screw O which extends through the top of the yoke into a screw threaded recess in the upper end of the wedge block. A pin o prevents the bolt O from moving vertically 120 with respect to the yoke.

n² designates a coil spring interposed between the inner surface of one part of the yoke and engaging a lug N² projecting from the lower end of the wedge block N', thereby 125 retaining the wedge block within the seat 130

formed in the yoke when the crank box is at the upper end of the yoke.

The operation of our invention is as follows: When the pistons are in the positions shown in Fig. 1, B' and B⁴ are in position to be driven by an explosion in the cylinders A' and A⁴, while the cylinders A² and A³ have drawn in a charge of motive fluid upon the rotation of the crank shaft 180°, while the pistons in cylinders A⁶ and A⁷ have been driven to the positions shown by explosions, and the burned gases will be driven out upon the next reciprocations of the pistons B⁶ and B⁷ due to the rotation of the crank shaft 180°.

15 The cams on the shafts K' and K² are staggered so that the exhaust valve in each cylinder will be unseated by the oscillation of the corresponding bell crank lever upon the return reciprocation of the piston after it has 20 been driven by an explosion. After the exhaust valve has been unseated the next reciprocation of the piston draws in a charge of motive fluid, the inlet valve being merely held to its seat by a light spring so that the 25 suction in the cylinder opens the intake valve and draws in a charge from a supply conduit not shown, which communicates with the passages in the lower cap G of each cylinder. The next reciprocation after the 30 piston draws in a charge, compressed the motive fluid, and it is exploded by suitable mechanism, the force of the explosion then driving the piston in a direction to rotate the shaft through the corresponding crank. The 35 cam which actuates each bell crank lever completes a revolution for each two reciprocations of the piston, such timing of the rotation of the cam being accomplished by the meshed spiral gears on the crank shaft and 40 exhaust valve-actuating rod L.

Provision for operating the engine in either direction is made by means of the combination of the key l on the shaft L and wide key-way in the spiral gear L², by thus 45 allowing the crank shaft and pistons to complete a cycle in the reverse direction before the valve operating rods K' and K² are put in motion, when they take their proper relative positions for reverse direction of the engine.

50 From the foregoing description it will be observed that we have invented an improved multiple cylinder explosive engine adapted to be operated in either direction, in which four pairs of aligned cylinders are employed and the cycles so timed that explosions occur simultaneously in cylinders on opposite sides of the shaft during each half revolution of the crank shaft, thereby balancing the engine 55 mechanically, explosively, and cyclically.

It will be further observed that in our improved engine the pistons in aligned cylinders are rigidly connected to a yoke, thereby avoiding the use of either trunk pistons, or 60 cross heads and connecting rods, and caus-

ing the two rigidly connected pistons to mutually guide each other, permitting the piston heads to be much shorter, thus greatly reducing the friction coincident with the use of the ordinary trunk pistons, and at 70 the same time affording a much longer guide for the pistons. Our improved construction also enables the wear incident to the reciprocations of the crank box within the yoke, and the yoke within the crank casing to be 75 eliminated, and also greatly reduces the friction and wear between the pistons and the cylinder walls. Our arrangement of pistons, yoke and valve mechanism thus permits the cylinders and engine to be materially shortened and the crank case to be 80 much shallower and more compact, reduces the number of working parts and permits the engine to occupy a comparatively small space, and it is therefore adapted for use on 85 car trucks or other vehicles in which the available space for the motor is small.

While we have described more or less precisely the details of construction, we do not wish to be understood as limiting ourselves thereto, as we contemplate changes in form, the proportion of parts, and the substitution of equivalents, as circumstances may suggest or render expedient, without departing from the spirit of our invention.

Having now fully described our invention, what we claim as new, and desire to secure by Letters Patent, is:—

1. In a multiple cylinder explosive engine, the combination with a crank shaft, 100 of a plurality of pairs of aligned cylinders, the cylinders in each pair located on opposite sides of the crank shaft, reciprocating pistons located within said cylinders and operatively connected to the crank shaft, 105 intake valves controlling the admission of motive fluid to the cylinders, exhaust valves unseating inwardly, stems on the exhaust valves projecting to the exterior of the valve casings, a cam shaft journaled adjacent the 110 stems of the exhaust valves, cams on the cam shaft adapted to successively actuate the valve stems and unseat the exhaust valves, a longitudinal shaft extending at right angles to the cam shafts, beveled gears 115 connecting the corresponding ends of the cam shafts to the ends of the longitudinal shaft, meshed spiral gears on said longitudinal shaft and the crank shaft, and means for adjusting said spiral gears to properly 120 operate the cam shafts when the engine is reversed.

2. In a multiple cylinder explosive engine, the combination with a crank shaft, of a plurality of pairs of aligned cylinders, the 125 cylinders in each pair located on opposite sides of the crank shaft, reciprocating pistons located within said cylinders and operatively connected to the crank shaft, intake valves controlling the admission of 130

motive fluid to the cylinders, exhaust valves unseating inwardly, stems on the exhaust valves projecting to the exterior of the valve casings, a cam shaft journaled adjacent the stems of the exhaust valves, cams on the cam shaft adapted to successively actuate the valve stems and unseat the exhaust valves, a longitudinal shaft extending at right angles to the cam shaft, beveled gears 10 connecting the corresponding ends of the cam shafts to the ends of the longitudinal shaft, meshed spiral gears on said longitudinal shaft and the crank shaft, means for adjusting said spiral gears to properly operate 15 the cam shafts when the engine is reversed,

bell crank levers fulcrumed upon the cylinder casing above the exhaust valves, one arm of each lever adapted to engage the stem of the corresponding exhaust valve and the other arm of the bell crank lever adapted 20 to be engaged and the bell crank lever oscillated by a cam on the cam shaft.

In testimony whereof, we sign this specification in the presence of two witnesses.

FRANK L. CHASE.
BERTRAND M. YOUNG.
